TAKEDOWN TYPE SWINGABLE WALL
BRACKETRobert E. McLean, Columbus, Ga., assignor to
John C. Hockery, Kansas City, Mo., as trustee

Application April 19, 1948, Serial No. 21,916

11 Claims. (Cl. 248—289)

1

This invention relates generally to the class of supports and pertains particularly to improvements in swingable, take down type wall brackets designed for the support of can openers of the rotary drive wheel type, fruit juicers or other kitchen devices which are designed to be mounted on a wall or other support for use.

The improved bracket mounting means herein disclosed embody certain improved features over my prior U. S. Patents No. 2,351,531 of June 13, 1944, and No. 2,427,613 of September 16, 1947, one important object of the present invention being to provide a bracket support which is designed to be moved vertically against the tension of a suitable retaining spring, to dislodge the device from a securing element whereby the bracket arm may be swung to the right or to the left to an out-of-the-way position.

Another object of the invention is to provide an improved swinging wall bracket having as an element thereof a notched cam, in which the bracket is engaged when in set-up or working position, wherein the bracket may be dislodged or disengaged from the retaining notch to be swung to the right or to the left to an out-of-the-way position, without first having to shift or disengage latches or pawls or other locking means, such movement of the bracket being effected solely by the operation of applying force thereto in a vertical direction as a preliminary to swinging the bracket laterally.

Another object of the invention is to provide a supporting bracket of the character described wherein there are employed two plate members one of which is permanently secured to a support while the other one is designed to be slidably engaged to the fixed plate, with means for establishing an interlocking connection between the arm and the two plates when the arm has been swung to operating position whereby the disengagement of one of the plates from the other is prevented until the arm is swung to the previously described out-of-the-way position.

Another object of the invention is to provide in a take down type swinging wall bracket of the character described, a fixed plate and a shiftable plate which is slidably engaged with the fixed plate and on which is pivotally carried an article supporting arm with spring means for normally urging movement of the article supporting arm in one direction on its swinging axis for engagement with a holding notch, and with means connected with the arm and adapted to turn therewith which, when the arm is in working position, functions to lock the two plates to-

2

gether whereby the shiftable plate cannot be disconnected from the fixed plate.

Still another object of the invention is to provide in a take down type swinging wall bracket of the character stated, a novel shiftable latching element between the fixed plate and the movable plate, which latching element is maintained against movement in a direction which would release the plates one from the other, so long as the bracket arm is in operative position, the swinging of the bracket arm to inoperative or out-of-the-way position simultaneously releasing the latching element for shifting movement whereby the connection between the two plates may be broken.

Other objects and advantages of the invention will become apparent as the description of the same proceeds and the invention will be best understood from a consideration of the following detailed description taken in connection with the accompanying drawings forming a part of the specification, with the understanding, however, that the invention is not to be limited to the exact details of construction shown and described since obvious modifications will occur to a person skilled in the art.

In the drawings:

Figure 1 is a view in elevation of the left hand side of a bracket constructed in accordance with the present invention, the outer end portion of the supporting arm being broken away.

Figure 2 is a view in front elevation of the same, the supporting arm being in transverse section.

Figure 3 is a view in top plan of the structure as illustrated in Figure 1.

Figure 4 is a view in elevation of the fixed or wall attached plate per se.

Figure 5 is a sectional view taken substantially on the line 5—5 of Figure 3, with the bracket arm, sleeve and post remaining in elevation.

Figure 6 is a view in front elevation of a second embodiment of the invention, the bracket arm being in transverse section.

Figure 7 is a view in bottom plan of the second embodiment shown in Figure 6.

Figure 8 is a vertical section, corresponding to Figure 5, through a third embodiment of the invention, the arm, sleeve, supporting post, spring and latch remaining in elevation.

Figure 9 is a transverse section taken substantially on the line 9—9 of Figure 8.

Figure 10 is a vertical section corresponding to Figure 5 of a fourth embodiment of the invention, the arm, post and spring remaining in elevation.

Figure 11 is a view in front elevation of the embodiment shown in Figure 10, the arm being in transverse section.

Figure 12 is a horizontal section taken substantially on the line 12—12 of Figure 10.

Referring now more particularly to the drawings wherein the first embodiment of the invention is illustrated in Figures 1 to 5 inclusive, the numeral 10 generally designates one of the two relatively movable plates of the bracket structure, this plate being designed to be secured to a wall or other fixed support. The fixed plate 10 comprises a back portion 11 through which are formed the suitable openings 12 for the passage of mounting screws or the like. The opposite longitudinal edges of the fixed plate 10 are turned in to form the spaced parallel guide flanges 13 which flanges, as are clearly shown in Figures 1, 3 and 5, are spaced from the front face of the body plate 11 to provide the guide channels 14.

The body portion 11 of the fixed plate has formed therethrough in the center thereof, the rectangular opening 15 for the purpose herein-after set forth.

The numeral 16 generally designates the shiftable plate which is connected with the fixed plate and maintained in position in front of the same by the flanges 13. This shiftable plate 16 comprises the flat back portion 17 which is of an overall width substantially equal to the width of the space between the confronting faces of the channels 14, as shown in Figure 3.

The top and bottom edges of the shiftable plate 16 have integral therewith the forwardly directed ears 18 and 19 respectively, the ear 19 being of an overall width slightly less than the width of the space between the confronting edges of the flanges 13 as shown in Figure 2, while the ear 18 is of the same width as the back plate 17. Thus it will be seen that when the longitudinal edges of the back plate are disposed so that they can be slid down in the channels 14, the lower ear 19 will pass down between the flanges 13 while the top ear 18 will come to rest upon the top edges of the flanges 13 as shown in Figure 3, thereby limiting the downward movement of the shiftable plate with respect to the fixed plate. The overall length of the shiftable plate is such that when it is in this position upon the fixed plate the ears will have the fixed plate disposed therebetween.

The top and bottom ears 18 and 19 are provided respectively with the openings 20 and 21 which are in alignment to receive the pivot pin or post 22 which extends between the ears as shown and has its top and bottom ends turned or swaged as indicated at 23 to maintain it in position between the two ears.

As shown the top and bottom ears 18 and 19 of the shiftable plate are substantially semi-circular in form and the top ear 18 has formed integral therewith, throughout the semi-circular part of the edge thereof, the downwardly directed camming flange 24, which edge is of gradually increasing height from each of the two sides of the ear to the center point between the two ends of the curved edge portion. At this point the cam flange is provided with the notch 25 for the purpose hereinafter described.

The shiftable plate 16 has the back portion 17 thereof provided with a rectangular opening 26. This opening is of the same height as the opening 15 but is of greater width as is clearly shown in Figure 2, and the openings are in registration

one with the other when the two plate members are coupled together.

Numerical 27 designates a supporting bracket arm which is formed of relatively wide flat material. The inner end of this arm is turned upon itself to provide the sleeve 28, which sleeve receives the pivot post 22 as shown. The terminal portion of the end of the arm from which the sleeve is formed is brought back against the main body part of the arm to which it is secured by the rivets 29.

The outer end of the supporting arm 27 is not here illustrated. Such outer end of the arm may be in the form of a cam opening drive or any other suitable kitchen accessory and has no patentable relation to the present invention.

As is shown the height or length of the sleeve 28 is materially less than the height of the same space between the ears 18 and 19 and in this embodiment of the invention, the pivot post 22 has positioned therearound, between the lower ear 19 and the lower end of the sleeve 28, the relatively strong expansion spring 30 which constantly urges the arm 27 upwardly so as to bring the top end of the sleeve 28 and the top edge of the arm into contact with the underside of the top ear 18, when the arm 27 is swung to the right or to the left to an out-of-the-way position or to bring the top edge of the arm into contact with either of the two sides of the camming surface 24.

When the arm 27 is swung about the post 22 to a position where it is perpendicular to the face of the plates 10 and 16, the top edge of the arm will engage in the notch 25 as illustrated in Figures 1, 2 and 5, the spring 30 functioning to force the arm upwardly into the notch whereby the arm will be firmly held against swinging movement.

A portion of the sleeve 28 is cut away and is bent back to extend radially from the sleeve and post substantially in line with the arm 27 to provide a locking tongue 31, Figure 3.

The height of the tongue 31 is materially less than the height of the openings 15 and 26, as is clearly shown in Figure 5, and the tongue is so positioned that when the arm 27 is in operative position, that is, is extending forwardly from the plates and has its top edge engaged in the notch 25, the top edge of the tongue will be substantially in contact with the top edges of the openings 15 and 26 and some little space will be left between the bottom edge of the tongue 31 and the bottom edges of the openings. This space allows for the necessary downward movement of the sleeve 28 against the tension of the spring 30 to permit the top edge of the arm to be disengaged from the holding notch 25.

Figures 6 and 7 illustrate a second embodiment of the invention wherein the elements carried by the movable or shiftable plate are in inverted order.

In this second embodiment the fixed plate, generally designated 31, is of the same construction as the plate 10 and accordingly it will be apparent that a detailed description of the same is unnecessary.

The shiftable plate for the second embodiment is generally designated 32. This shiftable plate comprises the back part 33 in which is formed, centrally between the ends and the two sides, the relatively large rectangular opening 34 which corresponds to the opening 26 and which, like the opening 26, cooperates with an opening in

the fixed plate, the latter opening being designated 15'.

The shiftable plate 32 has at its top end the forwardly turned ear 35 which is of a width equal to the width of the body 33 so that when the side edges of the body 33 are inserted in the guides of the fixed plate 31 this ear will come to rest upon the upper ends of the inturned flanges of the fixed plate to maintain the shiftable plate in position. The top ear 35 is not required to project as far forwardly as the ear 18, and, as shown in Figure 7, this ear is relatively short or narrow and is provided at the proper distance forwardly from the body 33 and between the side edges, with the necessary opening 36 to receive the upper end of the pivot pin 37.

The lower end of the body 33 of the shiftable plate has the forwardly extending ear 38, the outer edge of which is substantially semi-circular as shown in Figure 7 and at the inner ends of 20 the semi-circular portion the sides of this ear 38 are cut in to provide the notches 39 which permit the bottom ear to pass downwardly along the inturned flanges of the fixed plate.

Bordering the semi-circular portion of the bottom ear 38 and extending upwardly, is the cam flange 40, corresponding to the flange 24 and midway between the ends of this flange 40, at the high point of the cam, is a notch 41.

At the radial center for the curved or semi-circular edge portion of the bottom ear 38 a suitable opening 42 is provided to receive the lower end of the pivot pin or post 37. This post is fixed between the upper and lower ears 35 and 38 as shown.

The numeral 43 designates the support arm, the inner end of which is turned to provide the guide sleeve 44, through which the post 37 passes. This sleeve rests upon the top of the bottom ear 38 and the lower edge of the arm 43 engages in the notch 41 to hold the arm in operative position, which position locates the arm at right angles or perpendicular to the face of the mounting plates.

Encircling the post 37 above the sleeve 44 and interposed between the sleeve and the top ear 35 is the expansion spring 45 which resists upward movement of the sleeve upon the post.

The sleeve 44, like the sleeve 28, has cut therefrom, a securing ear, not shown, corresponding to the ear 31, which when the arm 43 is in operative position, extends through the aligned openings 15' and 34 and functions to prevent the movable plate 32 from being shifted upwardly out of engagement with the fixed plate 31.

Figures 8 and 9 illustrate a third embodiment of the invention. In this embodiment the body plate is generally designated 46 and like the other fixed plates, it has side edge portions turned in to form the guide flanges 47 and guide channels 48 and the flat back portion of the fixed plate, designated 49, is provided with the rectangular opening 50 for coaction, as hereinafter described, with a securing latch.

Slidably engaged with the fixed plate 46, is the shiftable plate 51 having at its upper and lower ends the forwardly directed upper and lower ears 52 and 53 respectively which are provided with the openings 54 and 55 in which are engaged and secured the ends of the pivot post 56.

The bottom ear 53 may be of the same general size and contour as the ear 38 whereby such ear can readily pass downwardly between the opposed edges of the inturned flanges 47 while the top ear 52, being of an overall width equal to the

width of the back part 56 of the shiftable or hinge plate, will engage the top ends of the flanges 47 when the side edges of the back of the shiftable or hinge plate are slid down in the channels 48, to prevent further downward movement of such hinge plate.

The outer semi-circular edge portion of the bottom ear 53 is provided with the upstanding cam flange 57 which is of the same form as the flange 40.

The numeral 58 designates the supporting arm, the inner end of which is formed to provide the sleeve 59 through which the post 56 passes. This sleeve rests upon the top of the bottom ear 53 as shown in Figure 8, and is yieldably held thereagainst by the coil spring 60 which surrounds the upper end of the post 56 and is interposed between the top ear 52 and the top end of the arm sleeve 59.

The hinge sleeve 59 has formed therein upon the right and left hand sides of the arm, the recesses or openings 61, one only of which is here illustrated. These openings cooperate with a securing latch element which is generally designated 62 and which is carried by the shiftable or hinge plate 51.

As shown in Figures 8 and 9 the back part 56 of the shiftable plate 51 is provided, in a plane above the opening 50, with the laterally spaced slot 63. Below these slots there is formed the relatively large rectangular opening 64.

The latching or securing element 62 comprises a body plate portion 65 which has a total width equal to the distance between one outer side of 35 a slot or opening 63 and the outer side of the adjacent one. The top edge of the latch body 65 has formed integral therewith the two spaced right angularly and rearwardly directed lugs 66 which are loosely engaged in the slots 63 to 40 permit slight swinging movement of the latch element. Between these spaced rearwardly directed lugs, is a central forwardly directed lug 67.

The lower central part of the body plate 65 for the latch element has the depending rearwardly directed keeper knee 68 which, as shown in Figure 8 may be of substantially semi-circular form and the lower end of this knee terminates in the straight forwardly directed tongue 69 which is in close proximity to the back part 56 of the hinge sleeve 59. This tongue is also in a plane to enter either of the openings 61 when the arm 58 is swung to the right or to the left, to a position where it is substantially parallel with the face of the hinge plate body 56.

The latch knee extends into and through the opening 64 and is adapted to engage in the opening 50 of the fixed or wall plate 46 as shown in Figure 8. When it is in this position it holds the two plates 46 and 51 against relative movement so that the hinge plate cannot be disengaged from the fixed wall plate. Also it will be seen that when the arm 58 is in operative position or is perpendicular to the face of the hinge plate, the latch element cannot be shifted outwardly at its lower end to disengage the knee from the two openings 50 and 64. This shifting can only be accomplished when the arm 58 is turned to one side or the other where one of the openings 61 will be in a position which will permit the tongue 69 to swing forwardly to a sufficient extent to remove the knee 68 from the opening 50.

Figures 10, 11 and 12 illustrate a fourth embodiment of the invention wherein the notched

cam flange is carried by a part which is separate from the hinge or shiftable plate.

In this fourth embodiment of the invention the fixed or wall plate which is generally designated 70 is of the same construction as the wall plate 10.

The shiftable or hinge plate of this embodiment is generally designated 71 and comprises the flat back or body portion 72 which has at its top and bottom ends the forwardly directed ears 73 and 74 which are of corresponding length but different widths. The ear 73 which is at the top of the hinge plate is, as shown in Figure 11, of an overall width equal to the width of the hinge plate, while the lower ear 74 is of a width to pass downwardly between the guide flanges of the wall plate 70.

The ears 73 and 74 have therein the vertically alined openings 75 and 76 which receive the upper and lower ends of the pivot pin 77.

As will be readily seen upon reference to Figure 11 the top ear 73 functions, like the ear 13, to limit the downward movement of the hinge plate with respect to the fixed wall plate 70.

The numeral 78 designates the arm, the inner end of which is turned to provide the guide sleeve 79 which slides on the post 77. The sleeve 79 rests upon the lower ear 74 as shown and it has formed there from the rearwardly turned securing lug 80 which is swung into and extends through the alined openings 81 and 82 which are formed respectively in the shiftable or hinge plate and the fixed wall plate, when the arm 78 is in a position where it is perpendicular to the face of the two plates. Thus it will be seen that this securing lug 80 functions to lock the two plates together when the arm 78 is in operative position and since in this embodiment of the invention it is not necessary to shift the sleeve 79 upwardly against the tension of the spring 83 which surrounds the upper end of the post 77 and is interposed between the sleeve 79 and the top ear 73, in order to free the arm to swing to the right or to the left, the openings 81 and 82 are of the same height and are also of a height only slightly greater than that of the lug 80.

The numeral 84 designates a shiftable cam plate which is interposed between the top end of the sleeve 79 and the upper ear 73 and has the spring 83 resting upon the top thereof. This plate 84 has an opening 85 formed therein for the passage therethrough of the post 77 and such opening is preferably formed by cutting out a strip of metal which is turned upwardly to form the actuating finger 86.

The outer or forward edge of the plate 84 is substantially semi-circular and it has formed integral with the underside thereof the downwardly directed cam flange 87 which, midway between its ends and at the high point, has the notch 88 in which is received the top edge of the arm 78.

In a plane passing over the top edge of the arm 78, the shiftable or hinge plate body 72 has a transverse or horizontal slot 89 formed therein. This slot receives a rearwardly extending lug portion 90 forming an integral part of the plate 84, as shown in Figure 12. The opening 89 is of sufficient height to permit the lug 90 to have some free movement whereby the plate 84 can be swung upwardly slightly against the tension of the spring 83, to a sufficient extent to disengage the top edge of the arm 78 from the notch 88. This actuation of the plate 84 is accomplished by

the application of rearward pressure to the actuating finger 86, as will be readily apparent.

In the first three embodiments of the invention it will be readily seen that the disengagement of the arm from its securing notch is effected by applying force to the inner end of the arm in a direction to shift the hinge sleeve longitudinally of the supporting post against the tension of the spring surrounding the post. After such shifting movement of the sleeve on the post has been brought about to the desired extent, the arm will be free so that it can be swung to the right or to the left. Also after the arm has been so swung either to the right or to the left the two plates will be disconnected or freed one from the other by the securing lug, either the type of lug which forms an integral part of the sleeve or the freeing action may be accomplished by actuating the latch 62, whereupon the shiftable or hinge plate can be moved upwardly to disengage it from the fixed wall plate. In all of the embodiments the freeing of the arm for turning movement either to the right or to the left from operative position, is contingent upon the compression of a spring element which functions to maintain locking connection between the arm and the notch in the center or high point of the camming flange.

In the fourth embodiment this compression of the spring is accomplished by shifting the spring pressed plate 84 rather than by the movement of the sleeve of the arm longitudinally of the pivot post against the tension of the spring as in the first three embodiments.

It will be readily apparent that in all of the embodiments when the arm is secured in the cam flange notch it will be firmly held in such position by the control spring so that the normal use of a can opener or other accessory mounted upon the outer end of the arm may be accomplished without fear of having the arm shift its position. However, release of the arm in order to shift it to an inoperative position is easily and quickly accomplished and it will also be apparent that the necessary disconnection of the hinge plate from the fixed wall plate is automatic upon swinging of the arm from the operative position.

In the fourth embodiment of the invention, as best seen in Figure 10, it will be seen that the locking lug 80 not only automatically locks the hinge plate 71 to the fixed or wall plate 70 against vertical movement at all times when the supporting arm 78 is in the operating position, in which it is illustrated, but also automatically locks the arm 78 to the fixed or wall plate 70 in such manner that the said arm 78 can have no vertical movement in relation thereto.

It will be observed that the supporting arm of any embodiment of the invention can be freely swung by the operator at all times when the arm is not engaged in the retaining notch of the cam plate, and without manipulation of any other part. Thus it will be seen that the supporting arm of any embodiment of the invention can be restored from an inoperative position to the operative position by merely swinging it thereto.

It will be seen that the supporting arm of any embodiment of the invention is frictionally retained in any inoperative position, after having been swung thereto, against accidental swinging from any such position.

It will be observed that the hinge plate, together with all parts borne thereby, of any embodiment of the invention can be readily and easily removed by being lifted upwardly until

clear of the fixed or wall plate at any time when the supporting arm is in an inoperative position and substantially parallel to the back portion of the hinge plate.

I claim:

1. A supporting bracket of the character described comprising a plate designed to be mounted on a support, spaced ears carried by the plate, a pivot pin connected at its ends to and extending between the ears, said pin being secured to the ears against axial movement relative thereto, an arm member having a hinge sleeve at one end, the sleeve being between the ears and having the pin extending therethrough whereby the arm may be swung around the pin as a center, means connected with the plate and having the arm detachably coupled thereto to maintain the arm in a predetermined working position relative to the plate, and spring means for yieldingly maintaining the arm and the plate connected means in coupled relation.

2. A supporting bracket of the character described in claim 1 wherein said spring means comprises a coil spring encircling the pin between an ear and an end of the sleeve and maintaining pressure upon and longitudinally of the sleeve for yieldingly maintaining the arm and the plate connected means in the stated coupled relation.

3. A supporting bracket of the character described comprising a plate designed to be mounted on a support, spaced ears carried by the plate, a pivot pin fixed to the ears between and connecting the ears, an arm, a sleeve on an end of the arm and having the pin freely extended therethrough facilitating swinging the arm around the pin as a center, a curved cam flange connected to the plate, the arm having a portion adapted to slide on the flange when the arm is swung around the pin, means for establishing a locking connection between the arm and the cam flange when the arm is in a predetermined position with respect to the plate, a spring exerting separating pressure against an ear and the adjacent end of said sleeve and yieldingly maintaining said locking connection, and means for effecting release of the locking connection against the action of the spring.

4. A bracket structure of the character stated in claim 3 wherein said cam flange is carried by one of said ears, the connection between the end of the arm and the pin being of slidable character whereby the arm may be moved axially of the pin, and said spring means being interposed between the other ear and the connection between the end of the arm and the pin.

5. A supporting bracket of the character described, comprising a plate designed to be mounted on a support, spaced ears carried by the plate, a pivot pin connected between and secured to the ears, an arm, means forming a hinge sleeve at one end of the arm and having the pin extending therethrough whereby the arm may be turned around the pin as a center, the sleeve being of a length materially less than the distance between the ears and resting at one end against one of the ears, a flange carried by the said one of the ears on which an edge of the arm rides in swinging the arm around the pivot pin, the flange having a notch for receiving the said edge of the arm to maintain the arm in a predetermined position relative to the plate, and a spring interposed between the other ear and the adjacent end of the sleeve and normally urging the arm in a direction to maintain engagement between the arm and the flange carrying ear.

6. A supporting bracket structure of the character stated in claim 5 wherein said spring is in the form of a coil encircling the pivot pin and interposed between the said other ear and the 5 adjacent end of the pivot sleeve.

7. A supporting bracket of the character described, comprising a plate designed to be mounted on a support, spaced ears carried by the plate, a pivot pin connected between the ears, an arm, a hinge sleeve at one end of the arm and having the pivot pin extending therethrough, the hinge sleeve at one end being spaced from an ear, a plate member attached to the first plate and extending forwardly therefrom over the top of the arm and the said one end of the sleeve, a spring encircling the pivot pin and interposed between the second mentioned plate and the adjacent ear and normally urging the second mentioned plate into contact with the adjacent end of the hinge sleeve, the second mentioned plate being movable away from the arm and sleeve against the tension of the spring, and a notched flange carried by the second mentioned plate for engagement with an adjacent portion of the arm, the said adjacent portion of the arm engaging in the notch of the flange to maintain the arm in a predetermined working position.

8. A supporting bracket of the character stated in claim 7 with a finger member formed integral with the second mentioned plate and extending upwardly therefrom to facilitate oscillation of the second mentioned plate against the tension of the spring for the release of the arm portion from the notch of the cam flange.

9. A supporting bracket of the character described, comprising a fixed plate, a movable plate, means for slidably coupling the plates together, said movable plate having a pair of spaced ears, one of said ears having connection with the fixed plate to limit the movement of the movable plate in one direction with respect to the fixed plate, a pivot pin mounted between and connected to said ears, an arm, a hinge sleeve carried by the arm and having the pivot pin, extending therethrough, means for establishing a releasable locking connection between the arm and the movable plate when the arm is moved to a predetermined position with respect to the movable plate, said plates having 50 aligned openings, a shiftable latching means separate from the arm and sleeve and extensible through the aligned openings for securing the movable plate against movement in the opposite direction with respect to the fixed plate, and co-acting means between the hinge sleeve and said latching means for maintaining the latching means extended through said aligned openings when the arm is in said predetermined position.

10. A supporting bracket of the character described, comprising a fixed plate, a movable plate, means for slidably coupling the movable plate with the fixed plate, a pair of spaced ears carried by the movable plate, one of said ears having engagement with the fixed plate and maintaining the movable plate against movement in one direction beyond a predetermined position with respect to the fixed plate, said plates having aligned openings, a pivot pin connected between said ears, an arm, a hinge sleeve at one end of the arm having the pivot pin extending therethrough for swinging movement of the arm around the pivot pin as a center, means for releasably holding the arm in a predetermined position with respect to the movable plate,

11

and a latching element carried by the hinge sleeve for extension through the aligned openings to couple the plates against disconnection when the arm is swung to the said predetermined position.

11. A supporting bracket of the character described in claim 10 wherein the arm and sleeve are movable axially upon the pivot pin, means normally urging movement of the sleeve in one direction on the pivot pin to hold the arm in the stated predetermined position, release of the arm from said predetermined position being effected by shifting the sleeve against said urging

12

means, and the said openings in the plates being formed to permit limited free movement therein of the latching means connected with the hinge sleeve.

5 ROBERT E. MCLEAN.
